UNITED STATES PATENT OFFICE

172,832

AUTOMOBILE DISPLAY TURNTABLE

David Bruce Johnston, Port Chester, N. Y.

Application November 2, 1953, Serial No. 27,413

Term of patent 14 years

(Cl. D80—1)

To all whom it may concern:

Be it known that I, David Bruce Johnston, a citizen of the United States of America and residing at 50 Haines Boulevard, Port Chester, New York, have invented a new, original, and ornamental Design for an Automobile Display Turntable, of which the following is a specification, reference being had to the accompanying drawing, forming a part hereof.

Fig. 1 is a perspective view of the automobile display turntable embodying my new design;

Fig. 2 is a side elevation view thereof.

I claim:

The ornamental design for an automobile display turntable, as shown.
